UNITED STATES PATENT OFFICE

151,443

DESIGN FOR A DOOR KNOCKER

Edward T. Fraim, II, Lancaster, Pa., assignor to
E. T. Fraim Lock Company, Lancaster, Pa., a
corporation of Pennsylvania

Application January 9, 1948, Serial No. 143,605

Term of patent 14 years

(Cl. D10—7)

To all whom it may concern:

Be it known that I, Edward T. Fraim, II, a citizen of the United States, residing in Lancaster, Lancaster County, Pennsylvania, have invented a new, original, and ornamental Design for a Door Knocker, of which the following is a specification, reference being had to the accompanying drawings, forming a part thereof.

In said drawings:

Fig. 1 is a face view of the door knocker, showing my new design;

Fig. 2 is an end view of the door knocker;

Fig. 3 is a vertical sectional view on the line 3—3 of said knocker; and

Fig. 4 is a rear view of the knocker.

I claim:
The ornamental design for a door knocker, as shown.

EDWARD T. FRAIM, II.
